UNITED STATES PATENT OFFICE.

JOHAN F. FRITZ, OF PORTLAND, OREGON.

PORTABLE SAW TRACK.

Application filed April 1, 1921. Serial No. 457,711.

To all whom it may concern:

Be it known that I, JOHAN F. FRITZ, a subject of the King of Sweden, who have declared my intention to become a citizen of the United States, residing at Portland, in the county of Multnomah and State of Oregon, have invented a new and useful Portable Saw Track, of which the following is a specification.

10 My invention relates to devices for supporting portable power saws used for cutting logs lying on the ground and the object is to provide a light, portable, sectional track-frame for such saws, the construction 15 being such that the power saw is easily and rapidly moved from one cut of the log to the next.

In the drawing:

Fig. 1 is a top view of my portable frame comprising two sections and showing, in dotted lines, a portable power saw frame approximately in the position it occupies when making a cut.

Fig. 2 is an enlarged right hand end elevation of my device in operative position and showing a portable power saw making a cut in a log.

Fig. 3 is an enlarged sectional elevation on line 3—3 of Fig. 2.

30 Fig. 4 is an enlarged sectional elevation as on line 4—4 of Fig. 2.

Fig. 5 is an enlarged detail of one of the turnbuckle rods.

Fig. 6 is an enlarged sectional elevation on line 6—6 of Fig. 1.

Fig. 7 is an enlarged sectional elevation on the lower part of line 7—7 in Fig. 2.

Fig. 8 is a detail view showing a modified form of mounting the track wheel on a portable power saw.

Fig. 9 is a top view of Fig. 8 with the wheel 29 omitted.

Referring to the drawing by reference numerals the preferred form of my device 45 consists of a rectangular sectional frame of pipe construction with two parallel rails 9, 10 normally in position parallel to the log to be cut, said rails mounted on and connected with transverse frame bars as 11, 12 50 and 13 the upper ends of which extend beyond bars 9 and rest on a log 14 to be cut and the lower ends with their connections resting on the ground or blocked up as at 55 slightly above the ground on a common level.

The rails or track bars 9 and 10 constitute

the track on which the frame of a portable power saw (shown dotted in Fig. 1) can be moved along parallel to the log, 10 being the track on which a flanged wheel 17, 60 placed on lower end of saw frame, rolls, the bar 9 becoming a rest for clips 18 with grooves 18^a and engaging rail bar 9.

The portable power saws particularly adapted for my device are of the wheel-barrow frame type having an engine 20 mounted between the frame bars 19, a fly wheel 21, drive sprocket 22, link belt 23, a large sprocket 24 on a shaft 25 and driven by link belt 23, the outer end of shaft 25 70 having a crank 26 which in turn operates the saw 27 by means of a connecting rod 28. Some of said type of saws are moved about by means of the upper ends of frame bars 19 being used as handles and other types have 75 a wheel as 29 at their lower ends (see Fig. 8). On the latter type I remove said wheel, or it can be left on if not too large, and a special offset bracket 30 is bolted to members 19 by the shaft bolt 29^a, and has wings 29^b 80 bearing upon the frame, at one end, and the other end of the bracket is provided with a pin 31 which serves as an axle for the grooved wheel 17 which rolls on rail 10 of the frame.

85 The upper end portions of frame members 11, 12 and 13 are separate pipes 11^a, 12^a and 13^a, both sets of pipes connected in pipe crosses 32, and the rear ends of said members are threaded into angle T's 33 (see Fig. 90 2). Each pipe cross 32 receives a stub pipe 34 in its vertical pass, said pipe protruding through the lower end of the cross where it is threaded for a nut 35; the upper end of said pipe 34 is threaded at 34^x and permanently screwed into the lower leg of another pipe T 36 the head of which is normally transversely arranged with relation to frame bars 12 and the opposite arms of which are adapted to loosely receive bushings 37 protruding from the ends of pipe rail sections 9 in which they are fixed (see Fig. 6). T's 33 receive pipes 38 similar to pipe 34 with nuts 39 at their lower ends and their upper ends may be secured by pins 40^x in 105 T's 40 each of which has a long bushing 41 fixed in it and protruding from both ends to receive rail pipes 10 which are parallel to pipes 9. Each frame pipe 11, 12, 13 has a collar 42 (see Fig. 1) with eyes 43, each 110 of which is adapted to receive the end 44^a of a turn buckle rod 44 threaded at its op-

posite end for a turn buckle 45 whereby each frame section can be stiffened and held rigid to bar 12 which thus forms a part of it.

At the outer end of each pipe bar 11^a, 12^a, and 13^a I provide a collar 46 with a slot 47 adapted to guide the pointed arm 48 of a hook pivoted at 49 between ears of a collar 50 secured on the pipe 11^a, 12^a or 13^a. When the frame is placed on the log it is securely held against slipping by driving the pointed ends 48 into the log.

The clips 18 on power saw frame have each an L-shaped member 51 pivoted as at 52 and so located that when the saw is in position it is locked thereby said member 51 acting as a hook engaging the pipe rail 9; the slanting surface 52^x of the lower arm of the hook being such as to draw the parts together. As a further precaution I also provide a swinging arm 53 at the lower end of one of the power saw frame members 19, pivoted to the latter as at 54 and its lower end formed to straddle the frame bar 11, 12 or 13 according to location of saw frame.

It will be readily understood that in making my portable track the pipe T's 36 and 40 have an outside diameter corresponding to the outside diameters of the adjacent rail pipes 9 and 10 respectively, thus making continuous rails of even size.

The device is used in the following manner:

After first placing the track section including rails 9, 10, 11 and 12 in position 35 on a log, the power saw frame is placed approximately as shown dotted in Fig. 1, so that the saw will make a cut just outside of the frame bar 11 in Fig. 2. Then locking bar 53 on frame of the power saw is 40 swung into locking position on bar 11, and upper locking arm 51 is clamped over rail pipe 9 locking the sawing outfit in position. The turn buckle is manipulated to stiffen 45 the frame. Then the cut is made in the log and after completing the cut, the locking members 53 and 51 are released, saw is raised, the operator raises upper end of power saw frame in a similar manner to handling a wheel barrow and rolls the sawing outfit over onto next frame section 9, 10, 50 12 and 13 and engages the locking members 53 with the pipe 12 and the locking arm 51 with the rail 9 as before. The turn buckle and its bars are released and moved 55 over to the next frame section, as shown in dotted lines in Fig. 1. Pipes 9 and 10 of first section are released together with the bar 11 and these are then simply moved over to the left in Fig. 1 to form another frame section. This operation is repeated until 60 the entire log has been cut, the length of the rails 9 and 10 in all cases governing distances between saw cuts.

What I claim is:

1. In a portable device of the class described, a rectangular main frame section comprising two parallel spaced bars arranged transversely with relation to a log to be cut and with their upper ends adapted to rest on the log and the lower ends to rest on the ground, and two lateral spaced bars connecting the first mentioned bars and raised above the transverse bars to form rail members; a number of U-shaped auxiliary frames each comprising two parallel rail bars and one transverse bar, all identical with the corresponding bars of the main frame and all of said bars detachably connected and adapted to be assembled to form successive rectangular frame sections laterally on a log, a portable power plant on said rails of the rectangular frame and adapted to reciprocate a saw to cut the log in a line parallel to and adjacent one of the transverse bars of said frame and means for securing the rectangular frame section on the log and the power plant on said frame in coacting relation.

2. The structure specified in claim 1, said securing means comprising successively hooks pivotally secured in the transverse bars and having sharp points adapted to be driven into the log, and L-shaped hooks pivoted on the power plant and adapted to frictionally engage the rail bars of the rectangular frame.

3. In a device for sawing logs into certain lengths, a saw operating mechanism and a saw reciprocated thereby, a flat skeleton frame supporting the sawing mechanism and composed of two track rails extending parallel to the log to be sawed and three spaced parallel bars extending transversely under the rails to support them and adapted to rest partly on the log and partly on the ground, means for securing the frame to the log and means securing it to the sawing mechanism, said frame composed of sections detachably secured together, each section forming a U having its upper and lower arm securable to the middle one of the three bars and either of the three bars being suitable to serve as the middle bar.

4. In a device of the class described, a flat skeleton frame adapted to support a sawing machine movably mounted on it, said frame composed of separable sections involving three parallel spaced bars either one of which may be used as the middle one and rail sections detachably connecting the frame sections and forming a track for the sawing machine.

In testimony whereof I affix my signature.

JOHAN F. FRITZ.
